UNITED STATES PATENT OFFICE.

JOHN PRESSLEY COLEMAN, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA.

WHEEL AND LEVER STAND.

SPECIFICATION forming part of Letters Patent No. 746,793, dated December 15, 1903.

Application filed October 5, 1903. Serial No. 175,752. (No model.)

To all whom it may concern:

Be it known that I, JOHN PRESSLEY COLEMAN, a citizen of the United States, residing at Edgewood, in the county of Allegheny and State of Pennsylvania, have invented certain new and useful Improvements in Wheel and Lever Stands, of which the following is a specification.

My invention relates to stands which are employed for supporting or carrying wheels and levers employed in connection with switch and signal operating connections.

I will describe a stand embodying my invention and then point out the novel features thereof in claims.

In the accompanying drawings, Figure 1 is a view in elevation of a wheel-stand embodying my invention. Fig. 2 is a detail view, partly in elevation and partly in vertical section, of a portion of the wheel-stand shown in Fig. 1. Fig. 3 is a detail view, partly in elevation and partly in vertical section, showing a modification of my invention. Fig. 4 is a top plan of Fig. 1, but showing levers mounted in the stands.

Similar letters of reference designate corresponding parts in all of the figures.

The stand comprises end supports and bars intermediate the end supports, between which wheels or sheaves or levers are mounted. Each end support is made up of a number of sections or parts and comprises a base-piece a , a bolt a' , and fillers a^2 , which serve to space the bars. The base-piece a is adapted to be secured to a tie or other support, and it is provided with a recess to receive the head of the bolts a' . Preferably the recess will be angular to prevent the head of the bolt from turning; but separate means may be provided for this purpose. Each filler is preferably in the form of a collar, washer, or nipple, and means are provided for centering and retaining it centered about the bolt a' . As shown in Fig. 2, these means consist of an interior annular rib or projection a^4 , secured to or integral with the filler, or, as shown in Fig. 3, the means consists of a groove a^5 , provided in one or both surfaces of a bar to receive the edge or edges of adjacent collars.

Instead of the annular rib one or more radial projections may be employed.

$B B'$, &c., designate bars which extend between two end supports. At least two bars are required for each stand. Additional bars are employed according to the number of superimposed wheels or levers required. The bars $B B'$, &c., may be of any desired length between the end supports.

W designates the wheels or sheaves. The sheaves may be fast on shafts w , or they may be loosely mounted on the shafts. More than one sheave may be arranged on a single shaft if the sheaves are arranged directly above one another. If the sheaves are staggered in the stand, a shaft may be provided for each sheave. The shafts w are suitably journaled in the bars. As here shown, they fit in openings provided for them in the bars. Cotter-pins w^2 or other means may be provided for retaining the shafts in their journals.

Instead of sheaves being mounted in the stand levers L , of any type may be suitably mounted in the stand. (See Fig. 4.) In this figure I have shown a lever of the bell-crank type, suitably fulcrumed at its angle.

In assembling a stand the bolts of the end supports are passed through the base-pieces a , and then a bar and fillers are alternately placed on the bolts until the desired height of stand is obtained. A nut a^6 is then put on each bolt and the parts firmly clamped together by turning the nut on the bolt. Instead separate clamping means may be employed.

What I claim as my invention, and desire to secure by Letters Patent, is—

1. A stand for signal and switch operating connections comprising end supports made in separable parts and detachable bars.

2. In a stand for signal and switch operating connections, the combination of detachable bars, and end supports, each of which comprises a base-piece, one or more fillers and means for clamping together the base-piece, fillers and bars.

3. In a stand for signal and switch operating connections, the combination of detach-

able bars, and end supports, each of which comprises a base-piece, one or more fillers and a bolt, the bolt being adapted to clamp together the base-piece, fillers and bars.

5 4. In a stand for signal and switch operating connections, the combination of detachable bars, and end supports, each of which comprises a base-piece, one or more fillers, means for clamping together the base-piece, ¹⁰ filler and bars, and means for centering the filler or fillers.

5 5. An end support for stands for signal and switch operating connections comprising a base-piece, a filler or fillers, clamping means ¹⁵ and centering means for the filler or fillers.

6. An end support for stands for signal and

switch operating connections comprising a base-piece, a filler or fillers, a bolt and means for centering the filler or fillers about the bolt.

7. An end support for stands for signal and ²⁰ switch operating connections, comprising a base-piece, a filler or fillers, each of which is provided with an interior annular rib, and a bolt.

In testimony whereof I have signed my ²⁵ name to this specification in the presence of two subscribing witnesses.

JOHN PRESSLEY COLEMAN.
